LIQUID DISCHARGE APPARATUS

Harry C. Grant, Jr., New York, N. Y., assignor to
Specialties Development Corporation, Bloom-
field, N. J., a corporation of New Jersey

Application February 10, 1939, Serial No. 255,606

19 Claims. (Cl. 137—21)

The present invention relates to means for rapidly discharging the contents of a liquid storage tank, more particularly referring to the discharge of liquid fuel from the fuel tanks of aircraft in order to render such fuel tanks available for service as flotation members to buoyantly support the aeroplane and prevent it from sinking when its landing on water has become necessary.

More specifically, the present invention has reference to the liquid dumping method disclosed in the copending application of Henry Ernest Heigis, Serial No. 74,452, filed April 15, 1936, now Patent No. 2,195,213, granted March 26, 1940, and constitutes an improvement of the liquid discharge device shown and described in another copending application of Henry Ernest Heigis, Serial No. 139,710, now Patent No. 2,200,922, granted May 14, 1940, which was divided out of the first named application and filed April 29, 1937.

The present invention has been based on the broad method illustrated in the first named application wherein the opening of a closure controlling a discharge opening in the tank determines the subsequent steps of closing of the tank vent, the admission of fluid medium under pressure into the tank to aid in the evacuation thereof, and the rendering impervious of said tank after the evacuation of the liquid to maintain the buoyancy of the tank, now a flotation member. In the preferred embodiment of the method, as disclosed, use is made of fluid under pressure, specifically liquid carbonic acid, stored for that purpose on the aeroplane to operate the system and its elements.

As distinguished from the device of the second named application, in which a difference in pressure created with respect to the two sides of a fluid pressure operated piston due to the removal by fluid pressure of the closure of the tank discharge opening results in the redirection of the flow of the fluid medium under pressure to carry out the other steps of the method as referred to above, the present invention contemplates the use of structural means in conjunction with the fluid pressure operable closure means of the tank to control the redirection of the flow of fluid medium and thereby the steps subsequent to the removal of the closure means.

It is accordingly an object of the present invention to provide a liquid discharge device for a liquid storage tank adapted to be used as a flotation member which will prevent, under all circumstances, the entrance of fluid medium under pressure into the tank unless the closure of the

device has been removed to permit facile discharge of the liquid.

It is another object of the invention to provide a liquid fuel dumping device as part of an aeroplane flotation system which comprises a fluid medium flow control device, the operation of which is controlled by the closure of the tank opening.

Another object of the present invention is to provide a fuel tank dumping device which will control the operative flow of the fluid medium under pressure by which it is operated.

These and further objects of the invention will become apparent as the invention is described in greater detail in connection with the drawings, wherein:

Figure 1 is a view in section of a fuel storage tank including a plan view of the tank contents, dumping equipment constructed in accordance with the present invention and applied to a fuel tank in the wing of an aeroplane, the latter indicated diagrammatically.

Figure 2 is a view in section of the liquid dumping valve device which is the subject of the present disclosure, while Figure 3 is a top plan view of the dumping device of Figure 2.

Referring now to Figures 1 and 2, wherein like numerals designate like elements, the reference numeral 1 indicates an aeroplane liquid fuel tank mounted in the wing of a plane, 2 the fuel dumping device as arranged in the tank, 3 the pressure fluid medium inlet of the device, 4 the fluid pressure medium outlet of the device, 5 the fluid pressure medium storage container, 6 the fluid release of the container, 7 the pressure medium conduit from the container 5 to inlet 3, 8 the conduit from the fluid pressure medium outlet 4 to the combination tank venting control and fluid medium admission device 9, which operates to close the vent and to open the fluid medium admission valve to the tank, and 10 the air vent pipe to conduct air to the tank through the venting control. The details of the venting and fluid medium admission device will not be gone into, as it forms no part of the present invention and is fully disclosed in the above mentioned application, Serial No. 74,452, now Patent No. 2,195,213.

In Figure 2, the dump valve 2 is shown mounted inside the tank 1, part of the wall of which is illustrated in section, ring mounting 11 being welded into the tank surrounding a corresponding circular hole therein. This ring comprises a horizontal base flange portion which is welded to the tank wall, a vertical portion and an inwardly projecting horizontal flange onto which

is mounted, by means of screws 12, the body of the device proper 13. A ring form gasket 14 guards against leakage of any fluid medium within the tank to the outside. Body 13 of the device comprises a tank opening control portion and a fluid medium control mechanism operatively connected. The tank opening control portion consists of a circular valve 17 which seats with the circumferential gasket-like valve ring 18 on the valve seat 19 formed by the device body 13. Rivets 20 secure said valve ring 18 to the valve 17. The structure of the valve itself consists of a base ring 15 on which rests a spider-like formation having a central elevated body part 21 from which radiate eight legs or supports 22 as shown in Figure 3. Said body part 21 of the spider has a central bore 23 adapted to receive the stem 24 which is anchored by means of a pin 25 in a central recess 26 in the upper central part of valve 17. In an annular groove 27 formed concentrically with the bore 23 on the upper side of the body part 21 rests the expansion spring 28, the upper end of which bears against a collar 29 secured by a pin 30 to the uppermost part of stem 24. The flat upper side of valve 17 bears against a corresponding flat lower surface 16 of the spider body part 21. It will be seen that this arrangement permits of a movement of the stem and valve relative to the device body 13 downward and away from the seat 19 as a consequence of any pressure acting upon the surface of valve 17 and able to overcome the force of spring 28. This arrangement also permits of valve 17 to pivot at about pin 25 and the lower end of stem 24 to enable it to seat properly on seat 19 as an accurate alignment of the cooperating parts is not always obtainable. The lower side of valve 17 is concave, permitting the formation of a chamber 31, separated from the outside by the circular metallic disc closure 32 which is preferably of a non-ductile, crystalline and brittle nature and which is circumferentially secured to device body 13 by means of screws 33 and made leak-proof toward the outside by means of gasket 34. A circumferential, ring-like portion of disc 32 is separated from its main central portion by a deep circular groove 35 which has the purpose of weakening the disc along this line. The disc has rib-like formations 36 which serve to give added strength to its central portion relative to the grooved portion at 35. The disc, at a point just inside groove 35 is formed with a stud-like projection 36. Coaxially with stud 36, device body 13 is formed with a cylindrical formation 37 having a main chamber 60 and a connecting passage 61 between said chamber 60 and chamber 31 referred to above. Passage 61 is recessed and threaded to receive a hollow bushing 38 which carries secured between gaskets 39 and 40 disc 41, made of some easily rupturable material such as that known under the trade-mark "Celeron," or the like. This is to prevent entry into chamber 60 of any liquid that may have seeped past valve 17 due to vibrations during flight or a large liquid head on valve 17 and which would be filling chamber 31. Stud 36 is seen to be placed so as to partially extend into the hollow of bushing 38, occupying a position directly underneath the center of frangible disc 41. Cylinder chamber 60 is recessed and threaded at its top to receive a plug 42 which with gasket 43 forms a leak-proof closure of cylinder chamber 60 against any liquid within tank 1. A knob-like support 44 formed on the lower face of closure plug 42 carries detachably suspended by means of two springs 45, which

yieldingly grip said support, the tubular piston 46 closed at its lower end by piston head 47 and open at the top. Piston head 47 is formed with two stud-like projections; one, on the upper side of the piston, indicated at 48, carries secured thereto springs 45 by means of which the piston is suspended from support 44; the other, 49, on the lower side, projects into connecting passage 61 in exact juxtaposition to stud 36 on the other side of frangible disc 41. Piston head 47 is provided with passages 50, adapted to establish a fluid medium conductive communication between the spaces separated by piston head 47. The tubular piston itself forms a snug working fit within cylinder 37, chamber 60 of which has a cylindrical lining 51, held in place by a set screw 52 screwed into the wall of the cylinder, and preferably made of corrosion resisting metal, such as the alloy known as "Monel-metal." At the bottom of chamber 60 within cylinder 37 is placed the discoid gasket 63 which is formed with a central opening to accommodate the stud-projection 49 and is adapted to cooperate with the valve-like seat 64 formed on the under side of piston head 47. At right angles to cylinder 37, and forming an integral upper portion thereof, is cylindrical member 53 formed with passages 54 and 55 providing, respectively, an inlet and outlet for the fluid pressure medium with respect to chamber 60 through openings in cylinder 37 and its lining 51 provided therefor. Inlet and outlet conduits 7 and 8 are connected with passages 54 and 55 through connectors 3 and 4 which are threaded into corresponding recesses of the passages. Cylinder formation 53 terminates within tank wall 1 with a flat and flanged end 56 which is adapted to lie flat against the inside of said wall 1 and in line with an opening therein designed to accommodate connectors 3 and 4; the whole being held securely in place by bolt-ring 57 and bolts 58 which serve to clamp the tank wall 1 between flange 56 and bolt-ring 57; leak-proof connection is attained by provision of a gasket 59 between flange 56 and tank wall 1. The whole device may be removed from inside the tank when desired by simply unscrewing screws 12 and disconnecting screws 58 and bolt-ring 57. It is then possible to lift it out through the opening of base ring 11. In order to operate the device, pressure fluid medium is released from container 5 by actuation, manual or automatic, of its release 6. Pressure fluid medium now enters cylinder 37 by way of conduit 7, connector 3 and passage 54, and by its pressure causes suspended piston 46 to be disengaged from its support 44 and to descend toward frangible disc 41, thereby breaking the disc until stud 49 comes to rest upon stud 36 of the disc closure 32. Fluid medium continues to enter and passes from above piston 46 through passages 50, through connecting passage 61 into chamber 31 until the pressure therein forces out the disc closure 32, rupturing it at its weakest place, along groove 35. This deprives piston 46 and stud 49 of their support, namely stud 36, and the fluid pressure above piston head 47 now causes the piston to descend all the way to the bottom of chamber 60, and by means of coaction between seat 64 and gasket 63 effectively closing passages 50 and thus preventing any loss of the fluid medium to the atmosphere through the opening in the tank wall now created by removal of disc 32. At the same time, pressure medium inlet passage 54 is put in operative connection with outlet passage 55 into which the fluid

medium is now made to flow. Thence, the fluid medium passes through connector 4 and conduit 8 to venting and fluid medium admission device 9, causing tank vent pipe 10 to be closed to the atmosphere and the fluid medium admission valve therein, leading into tank 1 to be opened. When the pressure in tank 1 acting on valve 11 and made up of the head of the liquid and the pressure of the fluid medium in the tank is sufficient to overcome the tension of spring 28, valve 11 will be forced from its seat 19, and the liquid will drain to the atmosphere. It may be pointed out here that spring 28 is relatively quite weak, a proper liquid head in the tank being sufficient to permit drainage by gravity when disc 32 is removed. The gas admitted above the liquid into the tank under pressure is used to accelerate the dumping process apart from its function to provide buoyancy to the tank after emptying, while the spring is provided to reclose the valve rather than to withstand any pressure on the valve acting within the tank. Reclosing is, of course, essential, as the tanks are intended to be used as floats after evacuation of the fuel. The disc 32 is therefore the actual closure of the tank discharge opening, the main function of valve 11 being to prevent the loss of any gaseous fluid medium from the tank and to isolate the tank inside from any outside medium such as water. It is assisted in the latter function by the vent closing and fluid medium admission mechanism referred to above.

In order to make the device operative again, piston 46 is pushed upward until springs 45 catch hold of support 44 to keep the piston again suspended in its non-operated position; bushing 38 is replaced by another carrying a new frangible disc 41, and finally a new closure disc 32 is put in place of the remaining ring of the old one.

From the above, it may be seen that I have invented a device to quickly and positively drain a liquid from a tank at the same time making it possible to use the tank as a float.

It will be seen further that my invention accomplishes the various objects pointed out at the beginning of this specification. Finally, while my invention has been illustrated and described with specific reference to the accompanying drawings, it will be apparent to those skilled in the art that the invention resides in certain principles of operation and construction which may be embodied in various forms of construction without departing in any manner from the spirit and scope of the invention, and I therefore do not wish to be limited to the specific disclosure, but rather to the scope of the appended claims.

I claim:

1. In a discharge apparatus for a tank storing a liquid having a discharge opening, drainage control means for the tank including a closure associated with the opening adapted to be unclosed by fluid pressure, a source of fluid pressure, fluid medium conducting means from said source of fluid to said closure, fluid flow control means in said conducting means normally permitting the flow of fluid medium through said conducting means toward said closure and having a fluid medium outlet normally obstructed, and means associated with said closure to control said fluid flow control means.

2. In a discharge apparatus for a tank storing a liquid having a discharge opening, drainage control means for the tank including a closure associated with the opening adapted to be un-

closed by fluid pressure, fluid medium admission means for said tank, a source of fluid under pressure, fluid medium conducting means from said source of fluid to said closure, fluid medium conducting means from said source of fluid to said fluid admission means, means in said first named conducting means adapted to control the flow of fluid medium to the closure, and means associated with said closure to control said fluid flow control means.

3. In a discharge apparatus for a tank storing a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, means common to both said conducting means adapted to control the flow of fluid medium through both of said conducting means, and means associated with said closure to control said fluid flow control means.

4. In a discharge apparatus for a tank storing a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, partly in common with said first named conducting means, means common to both said conducting means adapted to control the flow of fluid medium through both of said conducting means, and means associated with said closure to control said fluid flow control means.

5. In a discharge apparatus for a tank storing a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, partly in common with said first named conducting means, means common to both said conducting means adapted to control the flow of fluid medium through both of said conducting means, and normally obstructing communication through said second named conducting means, and means associated with said closure to control said fluid flow control means.

6. In a discharge apparatus for a tank storing a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, partly in common with said first named conducting means, means common to both said conducting means adapted to control the flow of fluid medium through both of said conducting means and permitting communication through said first named conducting means, and means associated with said closure to control said fluid flow control means.

7. In a discharge apparatus for a tank storing

a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, partly in common with said first named conducting means, means common to both said conducting means adapted to control the flow of fluid medium through both of said conducting means normally permitting communication through said first named conducting means and obstructing communication through said second named conducting means, and means associated with said closure to control said fluid flow control means.

8. In a discharge apparatus for a tank storing a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means, partly in common with said first named conducting means, means common to both said conducting means adapted to control the flow of fluid medium through both of said conducting means normally permitting communication through said first named conducting means and obstructing communication through said second named conducting means, and means associated with said closure adapted by its position thereon to assure said normal position of the control means.

9. In combination drainage control means for a tank having an opening associated with said opening including a closure for the opening adapted to be unclosed by fluid pressure, means defining a fluid flow conducting path to said closure, means in said path adapted to control the flow of fluid medium to the closure, and means on said closure to control said control means.

10. In combination a fluid flow control valve, a liquid flow impeding member secured adjacent to the valve forming a chamber therewith and adapted to be rendered inoperative by fluid pressure, means defining a fluid flow conducting path into said chamber, fluid flow control means in said path normally nonobstructive thereto, and means on said flow impeding member to control said control means.

11. In a discharge apparatus for a tank adapted to store a liquid having a discharge opening, drainage control means for the tank including a closure associated with the opening adapted to be unclosed by fluid pressure, fluid medium admission means for said tank, a source of fluid under pressure, fluid medium conducting means from said source of fluid to said closure, fluid medium conducting means from said source of fluid to said fluid admission means partly in common with said first named conducting means, fluid flow control means common to both said conducting means movable by fluid pressure and initially set so as to permit communication through said first named conducting means and to obstruct communication through said second named conducting means, and movement limiting means for said flow control means on said closure adapted to be rendered inoperative by

fluid pressure with unclosing of the closure, whereby upon unclosing of the closure said flow control means is free to be moved to obstruct communication in the first and to free communication in the second named conducting means.

12. In combination a fluid flow control valve, a liquid flow impeding member secured adjacent to the valve forming a chamber therewith and adapted to be rendered inoperative by fluid pressure, means defining a fluid flow conducting path into said chamber, fluid flow control means in said path, fluid medium flow outlet means associated with said control means, and means on said flow impeding member to control said control means.

13. In combination a fluid flow control valve, a flow impeding member secured adjacent to the valve forming a chamber therewith and adapted to be rendered inoperative by fluid pressure, means defining a fluid flow conducting path into said chamber, fluid flow control means in said path, fluid medium flow outlet means associated with said control means normally obstructed thereby, and means on said flow impeding member to control said control means.

14. In combination a fluid flow control valve, a flow impeding member secured adjacent to the valve forming a chamber therewith and adapted to be rendered inoperative by fluid pressure, means defining a fluid flow conducting path into said chamber normally unobstructed, fluid flow control means in said path normally in a non-operated position adapted to be operated by fluid pressure, fluid medium flow outlet means associated with said control means normally obstructed thereby, and means on said flow impeding member to limit the operative movement of said control means adapted to become inoperative with unclosing of said member.

15. In combination a fluid flow control valve, a flow impeding member secured adjacent to the valve forming a chamber therewith and adapted to be rendered inoperative by fluid pressure, means defining a fluid medium conducting path into said chamber normally unobstructed, fluid flow control means in said path, normally in a non-operated position adapted to be operated by fluid pressure and upon operation to obstruct said path, fluid medium outlet means associated with said control means normally obstructed thereby adapted upon operation of said control means to be put in communication with said conducting path, and means on said flow impeding member to limit the operative movement of said control means adapted to become inoperative with unclosing of said member.

16. A spring controlled fluid flow control valve, having a body structure, a flow impeding member secured to said body structure forming a chamber therewith having a projection and adapted to be removed by fluid pressure, fluid flow distribution means on said body structure and forming a part thereof having a fluid inlet and a fluid outlet port, a fluid flow control piston operable by fluid pressure in said control means lightly held in an unoperated position in exact juxtaposition to said projection and in that position permitting fluid flow communication between said inlet port and said chamber and obstructing communication between said inlet and said outlet ports, whereby upon admission of fluid medium under pressure said piston is moved until further movement is stopped by said projection and upon removal of said projection with the flow impeding member

due to pressure in said chamber the piston is moved to the limits of said distribution means to interrupt said first named communication and to free said last named communication.

17. In a liquid flow control device operable by a fluid medium under pressure forming a chamber, a flow impeding member forming a closure for said chamber adapted to become inoperative upon application of fluid pressure in said chamber, means defining a fluid flow conducting path to said chamber including a control chamber, inlet means and outlet means for said control chamber, said outlet means leading into said chamber, a second outlet means for the control chamber, a fluid pressure operable fluid flow control member movable in said control chamber between said inlet and outlet means normally permitting free passage of fluid medium therebetween and obstructing passage of fluid medium between said inlet and said second outlet means, and means associated with said flow impeding member adapted to obstruct operative movement of the control member, whereby upon application of fluid pressure through said inlet means said movement obstructing means becomes inoperative and the control member is operated to obstruct communica-

tion between said inlet and outlet means and to free communication between the inlet and said second outlet means.

18. In a discharge apparatus for a tank storing a liquid having a discharge opening, a valve and a flow impeding member adapted to close said opening, fluid pressure means to unclose said member, fluid pressure means to unclose said valve, and means structurally associated and movable with said member for preventing operation of said last named fluid pressure means until said member has been unclosed.

19. In a discharge apparatus for a tank storing a liquid having a discharge opening, drainage control means for the tank including a closure associated with the opening adapted to be unclosed by fluid pressure, a source of fluid pressure, fluid medium conducting means from said source of fluid to said closure, fluid flow control means in said conducting means normally permitting the flow of fluid medium through said conducting means toward said closure, and means associated with said closure to control said fluid flow control means.

HARRY C. GRANT, JR.
